Barracuda Dr.B Aquarevol Swim Goggle, announced: unknown, [online], [site visited Jul. 14, 2018]. Available from Internet, <URL: <https://barracuda101.com/products/barracuda-dr-b-optical-swim-goggle-aquarevol-honeycomb-structured-gaskets-for-adults-94690>> (Year: 2018).*

Primary Examiner — Michelle E. Wilson*Assistant Examiner* — Sanjeev Paul(57) **CLAIM**

The ornamental design for a swimming goggle, as shown and described.

DESCRIPTION

FIG. 1 is a perspective view of a swimming goggle showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines in the FIG. 3 illustrate portions of the swimming goggle that form no part of the claimed design.

1 Claim, 7 Drawing Sheets
